UNITED STATES PATENT OFFICE.

CLAUDE A. SHATTUCK, OF HAGUE, NEW YORK.

BACK FOR SEATS.

1,366,506.

Specification of Letters Patent. Patented Jan. 25, 1921.

Application filed May 14, 1920. Serial No. 381,355.

To all whom it may concern:

Be it known that I, CLAUDE A. SHATTUCK, a citizen of the United States, residing at Hague, in the county of Warren, 5 State of New York, have invented certain new and useful Improvements in Backs for Seats; and I do hereby declare the following to be a full, clear, and exact description of the invention, such as will enable others 10 skilled in the art to which it appertains to make and use the same.

This invention relates to seats, and particularly to those which are plain boards such as used in boats and canoes; and the 15 object of the same is to produce a back capable of attachment to such a seat and adapted to be folded onto it when desired.

The invention consists more particularly in the peculiar means for clamping part of 20 the attachment to the seat and for hinging the back to said part and latching it when it stands upright; and while I have described my invention herein as applied to the seat of a boat, it is obvious that it could be 25 clamped to and used with other seats.

Details of construction are set forth below and shown in the drawings wherein:

Figure 1 is a side elevation partly in section showing this back as attached to the 30 seat and in full lines as raised and in dotted lines as folded.

Fig. 2 is a detail of the latch.

Fig. 3 is a plan view of the hinge and the upper end of the clamp.

Fig. 4 is a plan view.

The seat S herein shown is a plain board. The attachment includes a cleat 1 also of wood recessed or chamfered on its upper side as at 2 so as to underlie the seat at its 40 front end, and cut off on a slight bevel 3 at its rear end. The seat back is of any appropriate construction and preferably of light material such as wood, and its upright 4 is intended to pass down behind the rear 45 end of the cleat 1, to which it is hinged, and rest against the bevel 3 so that said upright will incline a little to the rear when the back is in use—the entire back being folded down over the seat when not in use, as seen 50 in dotted lines in Fig. 1. The hardware includes a clamp for connecting the cleat to the seat, a hinge for connecting the back to the cleat, and a latch for holding the back upright. Therefore the entire attachment 55 may be said to be made up of two wooden

elements and the necessary pieces of hardware, and it is quite obvious that it can be made and sold at a reasonable cost.

The clamp comprises a bolt whose shank 10 has a rib 11 extending along the rear side 60 of its upper portion, its upper end being turned forward into a hook 12 whose bill is widened and flattened to produce a lip 13 intended to overlie the seat S near its rear edge. This shank passes down through the 65 cleat 1 at the rear of its cut away portion 2, and its threaded end 14 projects below the cleat; and onto said end is strung a washer 15 and a hand nut 16 having a flange 17 at its upper end just beneath the washer. 70

The hinge comprises an upper leaf 20 bolted at 21 to the front of the upright 4, appropriate knuckles 22, and a lower leaf 23 bolted at 24 to the cleat 1 and having a notch 25 in its front end to engage the rib 75 11 so as to prevent the bolt-shank from turning in the hole in the cleat through which it passes. The lower leaf 23 of the hinge is preferably upbent a little at its rear end as at 26 so as to raise the pivotal 80 point sufficiently high to permit the seat back to be folded onto the seat S and to clear the hook 12.

The latch consists of a metal strip 30 which may be secured to the bottom of the 85 cleat 1 by the same bolt 24 that holds the lower hinge leaf, and the front end of this strip is given a double elbow to form a dropped finger 31 which is preferably slightly dished on its front end as at 32. 90 This finger underlies the flange 17 of the hand nut and prevents the latter from running off the screw threads 16 while it does not interfere with the rotation of the nut. In other words, this structure produces a 95 swivel mounting for the nut so that when it is turned to the left the entire clamping screw is pushed upward through the cleat and its lip 13 raised off the seat so that the device can be readily removed. The rear 100 end of the latch is given a second double elbow producing a catch 33, beyond which is a thumb piece 34; and in the rear lower corner of the upright 4 is mounted a wear plate 35 which may be held in position by 105 a screw 36. Thus when the back is raised until the lower end of its upright strikes the beveled end 3 of the cleat 1, the wear plate 35 passes over the thumb piece and the latch springs upward until its catch 33 en- 110

gages said plate. By this means the seat back is held upright until it is desired to fold it onto the seat, at which time it will be necessary to depress the thumb piece. 5 When the attachment is thus applied, a passenger can sit on the seat S and lean back in comfort. When it is desired to step over the seat or the use for the back has passed, the latch can be tripped and the back folded 10 down as seen in dotted lines. At other times the clamp can be loosened and the entire attachment removed.

I have shown and described but a single upright and hinge. The construction of the 15 seat back itself is not essential to this invention, and a single upright might support an appropriate back rest. If there be two uprights there should be two hinges and the cleat should be wide enough for both of the 20 hinges to be attached to it. In that case there could be two clamps and two latches, although one would probably be sufficient.

What is claimed is:

1. In a back for seats, the combination 25 with a cleat, and a clamp for attaching it to a seat and permitting it to project to the rear of the same, the clamp including a nut below the cleat provided with a flange; of a hinge connecting the front face of an up- 30 right of the back with the upper face of the cleat in rear of said clamp, and a latch secured to the lower face of the cleat for engaging the lower end of said upright

when raised, the front end of the latch having a finger underlying said flange. 35

2. In a back for seats, the combination with the upright of the back proper, a cleat chamfered in its upper forward corner to underlie the seat, and a hinge whose leaves are attached to the upper face of the cleat 40 and the front face of said upright; of a clamp including a shank passing through the cleat behind the seat and hooked forward, the bill of the hook being provided with a lip to overlie the seat, and a hand nut on the lower end of said shank. 45

3. In a back for seats, the combination with the upright of the back proper, a cleat chamfered in its upper forward corner to underlie the seat, and a hinge whose leaves 50 are attached to the upper face of the cleat and the front face of said upright; of a clamp including a shank passing through the cleat behind the seat and hooked forward, the shank having an upright rib and 55 the hinge leaf having a notch receiving said rib, a hand nut screwed onto the projecting lower end of the shank and having a flange, and a finger secured to the lower face of the cleat and underlying said flange. 60

In testimony whereof, I affix my signature, in the presence of two witnesses.

CLAUDE A. SHATTUCK.
